WARREN V. JOHNSON AND ROBERT C. KEPNER, OF BERWICK, PENNSYLVANIA, AS
SIGNORS TO THE AMERICAN CAR AND FOUNDRY COMPANY, OF NEW YORK, N. Y., A
CORPORATION OF NEW JERSEY

MINE CAR COUPLING

Application filed April 20, 1931. Serial No. 531,392.

This invention relates generally to mine cars and has for one object the provision of means for stiffening the car longitudinally thereof to resist end shocks and pulling 5 stresses.

Another object of this invention is the provision of a mine car including an underframe therefor longitudinally stiffened and reinforced to resist end shocks and pulling 10 stresses.

Still another object of the present invention is the provision of a new and improved combined bumper and coupler casting for use with mine cars.

15 A further object of this invention is the provision of a new and improved coupling means for mine cars.

Other objects and advantages of this invention will be apparent from the following 20 description taken in conjunction with the accompanying drawings in which:

Figure 1 is a view, partly in section, showing the adjacent end portions of two connected mine cars.

25 Fig. 2 is an end view of a mine car showing the present invention.

Fig. 3 is a top plan view of the car shown in Fig. 2, the view being taken at the end portion of the car and having certain parts 30 shown in section.

Fig. 4 is a sectional view on the line 4—4, Fig. 2, and

Fig. 5 is a sectional view on the line 5—5, Fig. 2.

35 Referring now more particularly to the drawings in which similar characters of reference designate similar parts in the several views, the drawings disclose a mine car having a body indicated generally at A, substantially

40 rectangular in the instance shown and comprising side and end walls 2 and 4, respectively. The drawings disclose a car designed for rotary dumping and hence the side and end walls are fixed or stationary.

45 Obviously the car may be designed for either end or side dumping, if desired. The car body is provided with a bottom which is shown as being formed of a plurality of longitudinally extending metal plates 6, and said

50 body is mounted on an underframe indicated

generally at B and which is of course provided with the usual wheels and axles (not shown). The underframe B comprises the spaced longitudinal sills 8, Z-shaped in the instance shown and having their upper 55 flanges 10 oppositely extending and outwardly projected to serve as supports for the body A (see Fig. 2). As clearly shown in Figs. 1 and 2, an angle 11 extends between and is connected to the lower flanges 12 of the sills 60 B by suitable fasteners 13, the horizontal flange 14 of said angle underlying the bottom flanges 12 of the sills to serve as a support for longitudinally extending wood planks 16, the ends of which project beyond the ends 65 of the sills to form parts of a bumper structure as hereinafter more specifically described. The angle 11 obviously defines an end sill and the vertical flange 18 of the angle 11 serves as an abutment for a bottom bumper filler block 20. The wood planks 16 extend from end to end of the underframe, and are also supported by the out-turned flanges 22 of buffer member C, in the form of an inverted flanged channel which extends from 70 end to end of the underframe and defines an underframe stiffener or back-bone, as will be apparent. The channel stiffener C extends beyond the end of the body and terminates adjacent the ends of the planks 16, which 75 latter are preferably rounded at their ends as shown clearly in Fig. 3; the wood planks and channel defining a bumper structure and supporting a combined bumper and coupler casting D secured thereto and to the stiffener 80 C by fasteners such as the bolts 24. As clearly shown in Figs. 1 and 2, the bolts 24 also serve to connect the filler block 20.

The casting D comprises a body portion including a face plate 26 adapted to extend over the ends of the planks 16 and the end of the channel stiffener C and said face plate defines a buffer. The face plate 26 is curved to conform to the curvature of the bumper structure and is provided with an inturned lower edge 27 underlying the forward edge of the filler block 20 to aid in supporting the latter. The coupler casting also includes a top plate 28 which rests upon the bumper structure and has an integral drawhead 30, 100

from the rear end of which a draw-bar 32 extends in a position such that it rests upon the web 34 of the channel C and is secured thereto by fasteners 36 which extend through and connect a brace 38 arranged in the channel, as clearly shown in Fig. 1. The angle 11 is also connected to the channel by means of a fastener 40 which extends through the draw-bar 32 and the channel and through the horizontal flange 14 of the angle.

From the description thus far it will be apparent that the underframe comprises a structure which is longitudinally reinforced by means of the metal channel C and which includes a buffer casting arranged over the bumper structure and connected to the backbone. As now to be described, the underframe also includes as an integral part of the buffer casting a coupling member, and as clearly shown in Fig. 1, the upper wall of the drawhead 30 is provided with a longitudinally extending opening 42 and with an upstanding hinge lug 44 to which the rear end of a coupler pin carrier 46 is pivoted on a pintle 50. The carrier 46 comprises a recessed cover which normally closes the opening 42 and pivotally secured within the forward end thereof on a pin 52 is a coupling pin 54 which normally depends from the cover and has its lower end arranged in a slot 56 formed in the lower wall 58 of a coupler socket 31. The forward end of the slot 56 defines a stop 60 for limiting the movement of the pin 54 in one direction, as will be apparent. The stop 60 is preferably alined with the forward end of the slot 42 formed in the upper wall of the drawhead, as clearly shown in Fig. 1. As will be apparent, the pin 54 is free to swing on its pivot 52 in one direction as shown in dotted lines in said Fig. 1 when a coupling link 61 enters the drawhead 30 to permit the engagement of the pin 54 with the link 61, and the movement of the pin 54 will be independent of the carrier 46. An uncoupling device or coupling pin lifting means is provided and as shown, the forward end of the carrier 46 is provided with a vertically extending stud 62 to which links 64 are pivotally connected by means of a pin 66. The upper ends of the links 64 are pivotally connected as shown at 68 to one end of a lever 70 which is adapted to be lifted by means of a rod 72 mounted in brackets 74 secured to the end wall 4 of the car body and provided with operating handles 76.

Arranged adjacent the cap 46 and pivotally secured to the end wall 4 is a keeper element 78 having a lower end 80 projecting outwardly from the end wall of the body. The keeper 78 is adapted to swing freely on its pivot 82 when the car is rotated for dumping purposes to a position such that the keeper arm 80 will overlie the cap 46 and serve to prevent swinging movement of the latter on the pivot 50 whereby to prevent lifting of the

pin 54 out of the link 61 and thus retain adjacent car bodies in their coupled relation.

From the above description it is believed that the construction of the present invention will be fully apparent to those skilled in the art. The drawings are for illustrative purposes only and various changes in the form and proportions of the construction may be made within the scope of the appended claims without departing from the spirit of the invention.

What is claimed is:

1. A coupling device for rotary dump mine cars comprising a draw head having an opening in its upper wall, a coupling pin support pivoted to the draw head adjacent the opening, a coupling pin pivoted to said support and normally extending through the opening into the draw head, said coupling pin being capable of movement in one direction independently of the support, means for swinging the support to lift the coupling pin, and a keeper pivoted to the car body adjacent the draw head adapted to engage the support when the car is rotated to restrain the support against movement on its pivot.

2. A coupling device for rotary dump mine cars comprising a draw head having alined openings in the upper and lower walls thereof, a coupling pin support pivoted to the draw head adjacent the opening in the upper wall thereof, a coupling pin pivotally connected to said support and normally extending into said openings, said coupling pin being capable of movement in one direction independently of the support, link and lever means for swinging the support to lift the coupling pin from the openings, and a keeper pivotally mounted adjacent the draw head adapted to engage the support when the car is rotated to restrain the support against movement on its pivot.

In witness whereof we have hereunto set our hands.

WARREN V. JOHNSON.
ROBERT C. KEPNER.
